(57) **CLAIM**

The design of an compressed air pistol with blowout nozzle,
as shown and described.

DESCRIPTION

FIG. 1 is a side view of an compressed air pistol with blowout nozzle showing my new design;

FIG. 2 is a perspective view thereof taken from the distal end;

FIG. 3 is a perspective view thereof taken from the proximal end;

FIG. 4 is a side view of an alternative embodiment of an compressed air pistol with blowout nozzle showing my new design;

FIG. 5 is a perspective view thereof taken from the distal end;

FIG. 6 is a perspective view thereof taken from the proximal end; and,

FIG. 7 is an enlarged perspective view of the distal end of each of the embodiments.
